GOLF TEE

Stanley J. Rogers, Churchill, Ohio

Application May 4, 1950, Serial No. 9,715

Term of patent 14 years

(Cl. D34—5)

To all whom it may concern:

Be it known that I, Stanley J. Rogers, a citizen of the United States, residing in Churchill, in the county of Trumbull and State of Ohio, have invented a new, original, and ornamental Design for a Golf Tee, of which the following is a specification, reference being had to the accompanying drawing, forming part thereof.

In the drawing:

I claim:

The ornamental design for a golf tee, substantially as shown.

STANLEY J. ROGERS.
